UNITED STATES PATENT OFFICE.

CARL C. RIOTTE, OF NEW YORK, N. Y., ASSIGNOR TO CARLTON R. RADCLIFFE, OF SAME PLACE.

DESIGN FOR AN ENGINE-FRAME.

SPECIFICATION forming part of Design No. 31,806, dated November 7, 1899.

Application filed May 9, 1899. Serial No. 716,174. Term of patent 7 years.

To all whom it may concern:

Be it known that I, CARL C. RIOTTE, a citizen of the United States, residing in the borough of Manhattan, city, county, and State 5 of New York, have invented or produced a certain new and original Design for Engine-Frames, of which the following is a specification.

This design relates to frames for engines, 10 and particularly to frames for marine engines.

My design provides an original shape for the frames, shells, or bodies of engines.

The new design is shown in the accompanying drawings, in which—

15 Figure 1 is a side elevation of an engine-frame embodying the new design. Fig. 2 is a plan view of the top thereof, and Fig. 3 is an end elevation thereof.

Referring to the drawings, A represents the 20 end of the base; A', the side thereof; B, the end of the pedestal, and B' the side thereof.

C represents the columns.

D represents the end of the body or capital, and D' the side thereof.

25 E represents the top of the capital.

A" represents a longitudinal projection on the base. F represents a cylindrical part of this extension, and G represents a lateral protuberance on the body.

30 According to the distinctive features of the new design the end A of the base is substantially semicircular, its side A' is substantially semicylindrical, its longitudinal projection A" is substantially semicylindrical on the side 35 and semicircular on its end and is of greater diameter than and concentric with the rest of the base, and the base and its projection have a narrow straight band at top, that of the base being lettered a and disposed above the axis

40 of the base and that of the extension being lettered a' and being disposed on a plane with its axis. The band a is of slight projection where it crosses the end A and of great projection along the sides. A cylindrical cavity

45 b is disposed on the end A and concentric therewith. Two rectangular square bands c c' surround this cavity. Beneath the band a the side A' has four parallel oblong projections b' and seven vertical projections b".

50 The end B of the pedestal is vertical, and its sides B' are inclined. Its bottom and top

are parallel. Two rectangular panels c" are disposed on each side wall, and each is surrounded by a border d. The pedestal has a band d' at its bottom.

Four cylindrical columns C are disposed above the pedestal and between it and the body. These are spaced apart equidistantly and connected at bottom by a border d". A fifth and smaller cylinder I is disposed between the two center columns, a horizontal cylinder I' crosses the two center columns from the top of the cylinder I, and two curved cylinders I" intervene between the ends of the cylinder I' and the bottom of the body or 65 capital.

The ends D of the capital are semicylindrical, and each has two ring-like projections f, and its obverse side wall D' is approximately a smooth parallel vertical wall of general rectangular shape. The reverse side wall D" of the body is in general of the same shape and appearance as the obverse wall. The obverse wall D' has four depending portions f' on its lower edge, each having a circular cavity. 70 The reverse wall D" has two protuberances G projecting from its lower side in a curve f". These protuberances extend vertically downward in a cylindrical portion g, parallel with the column C, and then diagonally downward in a cylindrical portion g', parallel with one side wall B' of the pedestal, and each has a band g" at its lower end.

The top wall E is flat and of general oblong shape, having parallel sides and semicircular 85 ends, and is crossed by an intersecting line h at its middle, which line coincides with a vertical line h', crossing the middle of the body.

Engine-frames embodying the new design have a distinctive appearance.

What I claim is—

The design for an engine-frame substantially as herein set forth and as shown in the drawings.

In witness whereof I have hereunto signed 95 my name in the presence of two subscribing witnesses.

CARL C. RIOTTE.
